UNITED STATES PATENT OFFICE.

WILLIAM BRADLEY, OF SHEFFIELD, ENGLAND.

CONSTRUCTION OF HIGH-PRESSURE WATER-TAPS.

SPECIFICATION forming part of Letters Patent No. 728,848, dated May 26, 1903.

Application filed December 3, 1901. Serial No. 84,504. (No model.)

To all whom it may concern:

Be it known that I, WILLIAM BRADLEY, a subject of the King of Great Britain, and a resident of 18 Collegiate Crescent, Sheffield, county of York, England, have invented certain new and useful Improvements in the Construction of High-Pressure Water-Taps, of which the following is a specification.

The object of my invention is to produce a tap the valve of which shall open suddenly to its full extent and shall close suddenly and which shall be retained in both positions by the pressure of the water in the body of the tap.

15 Referring to the drawings which form a part of my specification, Figure 1 is a vertical section of a tap made according to my invention. Fig. 2 is a vertical section of a tap modified in its construction, and Fig. 3 is a 20 sectional detail illustrating more clearly the construction of the valve.

The invention relates more particularly to the construction of float-actuated taps; but it may be applied to bib-taps and the like, if 25 desired.

By my invention the valve will open instantly to the full extent and will close suddenly when the water has risen to the desired height, the characteristic feature being 30 that the valve is first released from its seat by the action of the float-lever and then is opened to its full extent by water-pressure and held open. In its opposite action the valve is drawn down by the action of the 35 float-lever until when nearing the seating it is suddenly closed by the water-pressure and held closed.

In the drawings, I is the inlet, and O the outlet.

40 V is the valve; R, the valve-rod; L, the end of float-lever; M, the mouth of the outlet O; C, the valve-chamber; P, stifling parts; G, guide-piece; B, body of tap, and W W are waterways through the guide-piece.

45 The moving parts of the tap are the valve V, with its rod R, and connected guide-piece G.

The construction of the valve is shown more clearly in Fig. 3, in which it will be seen that the valve-rod R is provided with an annular 50 shoulder r and a threaded portion r' above the shoulder. A washer is placed upon this threaded portion and is clamped against the

shoulder by a disk v, having a threaded opening screwed upon the portion r'. In order to hold the outer edge of the washer, a threaded ring s engages the threaded exterior of the disk or nut v, and this ring is provided with an inwardly-extending flange s, bearing against the under surface of the outer edge of the washer. The guide-piece, which is tubular, 55 slides upon the tubular upper part of the outlet O and has two waterways W leading from the chamber C to the under side of the valve. The periphery of the guide-piece immediately below the waterways W and the annular edge 60 P of the reduced diameter of the chamber C when together act as a stifling-point and diminish the flow of water from the inlet to the outlet. Thus when the tap is in working order water enters at I and, passing through 65 the loosely-fitting parts, occupies the chamber C and adjacent spaces and holds the valve V firmly upon the mouth M of the outlet O. When the cistern is emptied, the float and lever L descend, and its nose N eventually 70 comes in contact with the top of the elongated slot S in the rod R and raises the valve V from the mouth of the outlet. This causes a 75 rush of water through the waterways W against the under side of the valve, which forces it upward to its full extent. In this movement the action of the water is reversed, the pressure in the first instance holding the valve down and afterward holding it up until it is drawn down by a superior force. When 80 this superior force is applied by the float-lever, the nose of which (as the water rises in the cistern) eventually comes in contact with the bottom of the slot in the rod R, the valve 85 is drawn down until, as it approaches the 90 mouth of the outlet, the stifle parts P come near together and so diminish the flow of water that a balance of forces or a point of equilibrium is reached, and the pressure of the water above the valve, aided by the float-lever, suddenly overcomes the resistance of the diminishing outflow on the under side of the valve and shuts it down.

In Fig. 2 I have shown a tap in which I employ an additional valve or disk D upon the 100 valve-rod R and located, like the valve in Fig. 1, above the inlet I, the valve in this case being situated below the inlet in the chamber C. The said disk D opens and

2
closes the waterways W from the inlet to the outlet, and the parts P and the lower edge of the disk act as stifling parts. The valve V closes against the mouth M of the tubular outlet O, and the nose N of the float-lever L engages with a slot S in the rod R, as in Fig. 1. In this tap when the valve (with its rod and disk) is raised from the mouth of the outlet O, permitting an escape of water from the outlet, the water from the inlet drives the disk D up to the top of its chamber and opens the connected valve to its full extent. When closing, by the action of the lever L, the flow is stifled by the disk and parts P, and the valve suddenly closes and is held closed by the pressure of water upon its upper surface, it being understood that neither the opening through which the rod R moves nor the fit of the disk D are made water-tight or prevent its passage into the chamber C.

In applying my invention to a tap to be operated by hand a suitably-formed finger-lever would replace the float-lever L and would be connected with the valve-rod R where preferred. In regard to the opening of the valve it may be noticed, however, that the slot S in the lower end of the valve-rod is longer than the width of the arm N of the float-lever, so that there is a limited movement allowed to the one part without affecting the other.

Having now described my invention, what I claim as new, and desire to secure by Letters Patent, is—

1. In a high-pressure water-tap, the combination with the casing having a valve-seat, of a valve having a suitable stem or rod, a float-lever having a loose connection with said rod whereby a limited movement of said parts with relation to each other is permitted, an annular stifle-wall or part in proximity to the water-inlet and a movable part connected with the valve to move therewith, said stifle and movable parts serving to materially restrict the water-inlet when the valve is near its seat but not seated thereon, substantially as described.

2. In a high-pressure water-tap, the combination with the casing, having a valve-seat and a water-inlet around said valve-seat to a

space above the valve, of a valve having a 50 suitable stem or rod, a float-lever having a loose connection with said rod whereby a limited movement of said parts in relation to each other is permitted, an annular stifle-wall valve-seat serving to contract said water-inlet, and a movable part connected with the valve and coöperating with said stifle-wall to materially restrict the inflow of water when the valve is nearing its seat but not seated thereon, substantially as described. 60

3. In a high-pressure water-tap, a casing, an annular wall within the casing providing a water-outlet and a valve-seat at the upper edge of said wall, a water-inlet at the side of the casing communicating with the upper part 65 of the casing through the annular space encircling said wall, a valve in the casing coöperating with said valve-seat, a flange projecting inwardly from the casing in proximity to the water-inlet, a movable flange or wall connected with the valve and coöperating with said flange on the casing to restrict the water-inlet, a valve-rod depending through the water-outlet and a float-lever having a loose connection with said rod, substantially as de- 70 scribed.

4. In combination the valve-casing having a water-inlet in the side thereof and an upwardly-extending tubular wall within the casing forming a water-outlet, said wall extending above the water-inlet and providing a valve-seat at its upper end, a valve coöperating with said valve-seat, an annular guiding portion for said valve encircling said tubular portion and guided thereon, said annular portion having a water-passage, a stifling-flange on said annular portion, a corresponding stifling-flange on the casing in proximity to the water-inlet, and means for imparting initial opening or closing movement to the valve, 80 substantially as described. 85

In witness whereof I have hereunto set my hand in presence of two witnesses.

WILLIAM BRADLEY.
